UNITED STATES PATENT OFFICE.

WILLIAM CAMERON, OF CHICAGO, ILLINOIS.

MACHINE FOR DOUBLE-SEAMING CANS.

1,170,798.

Specification of Letters Patent.

Patented Feb. 8, 1916.

Application filed January 2, 1914. Serial No. 809,889.

To all whom it may concern:

Be it known that I, WILLIAM CAMERON, a citizen of the United States, residing at Chicago, in the county of Cook and State of Illinois, have invented certain new and useful Improvements in Machines for Double-Seaming Cans, of which the following is a specification.

My present invention relates in general to machines employed in the manufacture of tin cans and has more particular reference to machines for fastening the can caps, or ends, onto the previously formed cylindrical bodies, the machine disclosed in the present instance being constructed to unite the can caps to the can bodies by what is commonly known as a double seam.

One of the primary objects of the present invention is the provision of a machine of this character which will operate entirely automatically at high speed, which will be simple and compact in structure, and in which the various moving parts will be covered and protected so that danger of injury to the operators will be reduced to a minimum.

Another object is to provide a machine in which the can bodies and caps will be fed in by gravity, thus eliminating the necessity of any positive feeding mechanism, this result being accomplished by constructing the machine so that the can bodies are fed in and operated upon while in horizontal position and the can caps are fed in in vertical position adjacent to the bodies and seamed onto the bodies while said bodies are in horizontal position.

Another object is to provide improved means for releasing the caps from the magazine, for turning them from horizontal to vertical position and feeding them to the machine in predetermined relation to the can bodies.

A further object is to provide novel chucks and mechanism for operating the same to clamp the can caps onto the can bodies prior to and during the seaming operation.

A further object is the provision of improved seaming tools and novel mechanism for supporting and operating the same.

Further objects are to improve the general construction and arrangement of parts in machines of this general character and to so position, arrange and actuate the various parts that the machine will operate quietly

and rapidly for long periods with very little attention from the operator.

Other objects and advantages of this invention will be readily apparent as the same becomes better understood by reference to the following description when considered in connection with the accompanying drawings, throughout the various views of which like reference characters refer to similar parts.

Referring to the drawings: Figure 1 is a side elevation of a machine embodying my invention; Fig. 2 is a plan view, certain parts being shown in section taken on the line 2-2 of Fig. 1; Fig. 3 is a rear view of the machine, certain parts being shown in section taken on the line 3-3 of Fig. 1; Fig. 4 is a somewhat diagrammatical view showing certain portions of the driving and operating mechanisms; Fig. 5 is a detail view, showing the turret driving mechanism on the far side of the machine shown in Fig. 4; Fig. 6 is a side elevation similar to Fig. 1 with certain parts removed to show the turret and the path of travel of the cans through the machine; Fig. 7 is an enlarged fragmentary view showing the first step in the seaming operation; Fig. 8 is a similar view showing the second step in the seaming operation; Fig. 9 is an enlarged longitudinal sectional view taken through the turret and one set of chucks; Fig. 10 is a fragmentary side elevation of the cap holding and feeding mechanism; Fig. 11 is a view taken on the line 11-11 of Fig. 10; Fig. 12 is a plan view of the cap releasing mechanism at the bottom of the magazine; Fig. 13 is a sectional view taken on the line 13-13 of Fig. 12; Fig. 14 is a sectional view taken on the line 14-14 of Fig. 12, and Fig. 15 is a view similar to Fig. 14, showing the supporting fingers in reversed position.

By reference to the drawings it will be observed that the machine comprises a main frame, or body, 16 preferably of cast construction and shaped to support and inclose as far as possible the various operating mechanism which will be later described. The can bodies 17, which are cylindrical in shape with the ends flared outwardly to provide flanges 18, are deposited manually or otherwise in an inclined hopper or chute 19 supported at the feed end of the machine by a suitable bracket 21 assisted by truss rods 22 or other preferred means. The can

bodies, due to the inclination of the chute, are disposed to roll to the delivery end of the chute under the influence of gravity at which point they are received by the intermittently rotating turret 23, as shown in Fig. 6.

The can caps, designated generally by reference character 24, are contained in a magazine of suitable construction mounted adjacent the chute 19. This magazine, as best shown in Figs. 1 and 10 to 15 inclusive, comprises a plurality of vertical guide-rods 25 supported in sockets 26 having horizontally disposed portions 27 slidably mounted in guideways 28 formed upon the upper end of a supporting bracket 29. The sockets are adjustably supported on the guideways by bolts 31 engaged in slots 32 (Fig. 2) so that the guide-rods may be adjusted closer together or farther apart to accommodate can caps of various sizes. The base 33 of the magazine is annular in shape and provided with a plurality of, preferably four, radially disposed guideways or slots 34 adapted to receive and guide in their longitudinal movements cap supporting fingers 35, 36, 37 and 38 respectively. Each finger is provided with an upwardly projecting pin 39 engaging in an inclined slot formed in an oscillatory ring 41 overlying the fingers and guided in its movements by a cap-shaped member 42. It will be observed that slots 43 and 44, with which the pins of fingers 36 and 38 respectively engage, are inclined oppositely to the slots 45 and 46, with which the pins of fingers 37 and 35 respectively engage, with the result that when the ring 41 is rotated in one direction the pair of fingers 35 and 37 will be withdrawn from beneath the can caps while the other pair, comprising fingers 36 and 38, will be projected into the path of the caps while upon reverse rotation of the ring the fingers of each pair will be moved in the opposite direction. This result will be best understood from an inspection of Figs. 12 to 15 inclusive. In Figs. 12 and 13 the fingers 36 and 38 are disposed beneath the lowermost cap of the stack in the magazine while fingers 35 and 37 are withdrawn, as shown in Fig. 14. Upon oscillation of the ring 41 in a counter-clockwise direction viewing Fig. 12, fingers 35 and 37 will be inserted above the lowermost and beneath the remainder of the caps while fingers 36 and 38 will be withdrawn to release the lowermost cap, permitting it to drop from the bottom of the magazine while the remainder of the stack is supported by fingers 35 and 37, as shown in Fig. 15. Upon oscillation of the ring 41 in a clockwise direction, viewing Fig. 12, fingers 36 and 38 will be projected into the position shown in Fig. 13 while fingers 35 and 37 will be withdrawn into the position shown in Fig. 14. It will be mani-

fest that the caps are released in succession at predetermined intervals from the magazine by oscillation of the ring 41.

The ring 41 is oscillated by means of a continuously rotating vertically disposed shaft 47 mounted in suitable bearings on the bracket 29, provided at its upper end with a cap 48 loosely mounted thereon and carrying a crank pin 51 which is connected by a pitman or link 52 with a pin 53 secured to the ring 41 and projecting downwardly through a slot 54 formed in the base plate 33. Driving connection is established between the shaft 47 and cap 48 by a clutch member 55 splined on the shaft 47 and adapted to engage with a clutch face on the cap 48. The clutch member 55 is controlled from a bell crank lever 56 pivoted on the bracket 29 at 57 and adapted to be held by a pivoted spring controlled latch 58 to maintain the clutch in either closed or open position. This clutch or throw-out mechanism is provided so that the feeding of the caps may be stopped when desired without stopping the whole machine.

When the caps drop from the magazine they fall upon an inclined plate or guideway 59 shaped to turn the caps from a horizontal into a vertical position so that they will enter the guide-groove 61 adjacent one side of the chute 19 and will roll down this inclined guide-groove parallel with the can bodies and will be delivered to the turret 23 simultaneously with the can bodies. In other words, the cap releasing mechanism is timed with respect to the turret so that a cap is released and delivered to the turret each time an empty turret socket is brought into alignment with the chutes 19 and 61.

The shaft 47 is driven through the intermediary of beveled gears 62 from a cross shaft 63 driven by means of a belt or chain 64 from a counter shaft 65. This counter shaft has a pair of large gears 66 and 67 of equal size fixed thereon at opposite sides of the machine and the shaft is driven through gear 67 from a pinion 68 clutched on the main drive shaft 69 which in turn receives power through a pulley 71 from any suitable source. A manually operated clutch 72 of any well known or preferred construction is preferably employed to establish connection between the drive pulley and the pinion 68. A hand wheel 73 projects from one end of the shaft in position to be grasped for turning the machine over by hand when the power is thrown off.

The turret 23 is preferably made in two parts, as shown in Fig. 6, and is rigidly secured upon a turret shaft 74 mounted in suitable bearings at its ends on the main frame. The turret, as best shown in Fig. 9, comprises a body portion 75 secured to the turret shaft by pins 76 or otherwise, and two end members 77 and 78 respectively

adjustably keyed to the body by a key 79. The end member 78 is provided with a series of radially arranged sockets 81 adapted to receive and support one end of can bodies 17, and member 77 is provided with similar sockets 83 to receive and support the other end of the can bodies. Member 77 is also provided adjacent each body socket 83 with a cap socket 84 which, as will 10 be evident from Fig. 9, is deeper than the body socket so that a can cap will be held in the cap socket substantially concentric with the can body carried in sockets 81 and 83. From Fig. 2 it will be observed that 15 the end members 77 and 78 are so positioned that the sockets 81 and 83 lie in alinement with the can body chute 19 and the cap sockets 84 are alined with the cap chute 61. The can bodies and caps are delivered, 20 therefore, to their respective sockets from the chutes 19 and 61, as will be readily understood. In order to prevent the caps from dropping out of the cap sockets longitudinally of the turret I have provided each 25 socket 84 at its base and at the outer end of the turret with a flange 85, as shown in Figs. 6 and 9. These flanges hold the inner edges of the caps in the cap sockets and during the initial travel of the caps with the turret 30 they are also retained in their respective sockets by a plate 86 (Fig. 1) carried by a bracket 87 adjacent the cap end of the turret.

The turret is intermittently actuated to 35 cause a step-by-step rotation by mechanism which will now be described. Back of the counter shaft 65 and in substantially horizontal alinement therewith is mounted a transversely extending shaft 88 which is 40 driven from counter shaft 65 by means of a connecting shaft 89 and suitable beveled gears 91 and 92. A crank disk 93 (Figs. 2, 3 and 5) is fixed on the end of the shaft 88 remote from the beveled gears 91. The corresponding end of the turret shaft 74 is 45 equipped with a ratchet wheel 94 and an integral notched disk 95. An arm 96 (Fig. 5) is mounted to oscillate on shaft 74 adjacent to the ratchet wheel 94 and this arm 50 carries a pawl 97 adapted to engage with the teeth of the ratchet wheel 94 upon oscillation of the arm 96. The extremity of arm 96 is connected by an adjustable link or pitman 98 with a crank pin 99 on the 55 crank disk 93. At each revolution of the shaft 88 the arm 96 is swung to the left, viewing Fig. 5, thereby rotating the turret shaft through the pawl 97 and ratchet wheel 94 one step in its movement. The shaft is 60 locked against movement during the return of arm 96 by means of a finger 101 carried by lever 102 pivoted on the main frame at 65 103 and normally urged toward the notched disk 95 by a contraction spring 104. A block 105 having a curved face is mounted

on the arm 96 and the lever 102 is equipped with a pin 106 adapted to engage with the curved face of said block. When the parts are in the position shown in Fig. 5 the curved surface of the block will, through 70 the instrumentality of the pin 106, swing the lever 102 about its pivot to withdraw the finger 101 from engagement with the notched disk 95 so that the turret shaft may be rotated in a clockwise direction upon 75 movement of the arm 96 to the left. As this movement takes place the block 105 travels out from beneath the pin 106, permitting the finger 101 to engage with the periphery of the notched disk, and as soon as the notch 80 is brought into alinement with the finger at the end of the actuation by the arm 96 the finger will enter the notch and lock the shaft against rotation until the return movement of the actuating arm has been practically 85 completed. It will thus be understood that the turret is intermittently rotated by a step-by-step movement.

The movement of the turret carries the can bodies and caps into alinement with successive pairs of oppositely disposed continuously rotating chucks, one chuck of each pair being movable longitudinally to clamp the body and cap together between the chucks. The chucks are designated generally in Fig. 3 by reference character 107, 95 108, 109 and 111 respectively. Chucks 107 and 108 are substantially identical in construction and a detailed description of one of these chucks will therefore suffice for an 100 understanding of both.

Referring now to Figs. 2, 3 and 9 it will be observed that the main frame of the machine is provided with a bracket or casting 112 shaped to provide horizontal bearings 105 for the chucks 107 and 108. Within the bore of casting 112 is mounted a bushing 113, held in position therein by nuts 114 and 115 respectively, threaded onto the ends thereof and clamped against the casting 112. 110 Within the bushing a hollow chuck spindle 116 is rotatably mounted, to the inner end of which is secured a pinion 117 by means of a pin 118 or otherwise. Lock nuts 119 threaded upon a contracted portion of the opposite end of the spindle hold the spindle against longitudinal movement in the bushing. A chuck head 121 is carried by the inner end of the spindle and is capable of slight longitudinal movement relatively to 120 the spindle by reason of a slot 122 through which the pin 118 passes. While in the present instance the slot 122 is provided in a shank 123 to which the chuck head 121 is 125 screwed it will be obvious that the head and shank might be made integral if preferred. A block 124 adjustably mounted in the opposite end of the spindle is formed to provide a stud 125 extending beyond the end of the spindle. A cap 126 is threaded onto the 130

outer end of the bushing 113 and an adjusting screw 127 threaded through the cap abuts against the stud 125 forming an end thrust bearing for the rotating spindle. A lock nut 128 serves to hold the adjusting screw in adjusted position. A coiled expansion spring 129 is disposed between block 124 and the shank 123 of the chuck head to normally yieldingly urge the chuck head outwardly on its spindle. It will be evident that the compression on the spring 129 may be regulated by manipulation of the screw 127.

The chuck 107 is substantially identical with the one just described, and this chuck is also equipped with a pinion 131 disposed in alinement with pinion 117. These pinions are both driven at the same speed by a driving gear 132 rotatably mounted on the turret shaft 74 and meshing with pinions 117 and 131. A pinion 133 integral with the hub of gear 132 meshes with and is driven by the gear 67 with the result that the chucks 107 and 108 are continuously driven through this chain of gears from the driving shaft 69.

The chucks 109 and 111 are substantially identical in construction and a detailed description of chuck 111 which is shown in section in Figs. 2 and 9 will suffice for an understanding of both. The frame of the machine at this side is shaped to provide a supporting portion 134 in which is mounted a reciprocating block or housing 135 adapted to carry both chucks 109 and 111. The block or housing is cored for each spindle to receive a bushing 136 (Fig. 9) in which the chuck spindle 137 is rotatably mounted. A pinion 138 is secured to the spindle adjacent its inner end and upon the inner end of the spindle is threaded a chuck head 139 shaped on its inner face to fit the can cap, as shown in Fig. 9. An adjusting screw 141 abutting against a stud 142 provides an end thrust bearing for the spindle. The chuck 109 is provided with a pinion 143 and pinions 138 and 143 both mesh with and are driven by a gear 144 rotatably mounted on the turret shaft 74, which gear in turn is driven from the gear 66 through the pinion 145 integral with the hub of gear 144. It will thus be manifest that all of the chucks are rotated at one and the same speed and in the same direction and that chucks 107 and 109 are disposed in alinement at opposite ends of the turret to form the first pair between which the can bodies and caps will be positioned, and that chucks 108 and 111 are also mounted in alinement, forming the second pair of chucks between which the bodies and caps are clamped after leaving the first pair.

The block or housing 135 is reciprocated longitudinally at predetermined intervals, carrying the chucks 109 and 111 therewith,

by means of a bell crank lever pivoted in bearings 146 on the adjacent side of the machine and comprising an arm 147 connected at its upper end by links 148 to the housing and a downwardly projecting arm 149 equipped with a follower 151 adapted to be actuated by a cam 152 fixed on the shaft 89 (Fig. 4).

Each of the can caps 24 is shaped to provide an annular groove or channel 152 on its outer face, as shown in Fig. 9, surrounded by a shoulder 153, the margin of the cap being bent to form a flange 154. The chuck heads of the longitudinally movable chucks 109 and 111 are each formed on their inner faces to fit the caps and are provided with peripheral flanges 155 substantially equal in thickness to the depth of the cap shoulders 153, so when the heads are moved inwardly to clamp a can against its body the outer faces of the chuck head flanges lie substantially flush with the outer faces of the flanges of the cap, as shown in Fig. 7. The chuck heads 121 are preferably faced with a knurled steel plate or other similar means 156 to present a non-slipping surface to the corresponding end of the can body. The movement of the chucks 109 and 111 inwardly is sufficient to firmly clamp the can bodies and caps together and cause them to rotate with the chucks, and a firm clamping is insured by reason of the expansion spring 129 acting on the chuck head 121, which spring also compensates for any differences in the length of the can bodies.

Upon an upwardly extending portion 157 of the main frame at the rear of the machine is mounted a plurality of seaming tools which will now be described. The primary tool which preliminarily seams the can caps onto the bodies as they are rotated by the first pair of chucks 107 and 109 consists of a roller 158, best shown in Fig. 7, provided with a peripheral groove 159 which, as the roller is forced against the flange of the can cap, crimps the flange over onto the body flange substantially as shown in Fig. 7. A central flange 161 adjacent the groove 159 is adapted to overlie the outer face of the can cap margin and also to overlie the outer face of the chuck head flange 155 so as to prevent the upward bending of the metal of the cap and insure the proper crimping action. A groove 162 similar in all respects to groove 159 is formed on the roller on the opposite side of flange 161 thereby rendering the tool capable of being reversed on its bearing pintle 163 so that its length of service is doubled. The tool is mounted between the forks of a reciprocating bar 164 guided in a bracket 165 and adjustably connected by means of a threaded connection 166 with a head comprising the two pieces 167 and 168 between which a piece of rubber 169 or other yielding material is inserted

to permit a slight retractive movement of the tool when the longitudinal seam of the can passes thereunder. This yielding strip or member 169 enables the tool to be held firmly against the work without exerting undue pressure, such as might break the tin around the longitudinal seam of the can body when the tool engages therewith. A follower 171 is mounted on the head in position to be actuated by a cam 172 mounted on a shaft 173 which is driven from the shaft 88 by means of a chain 174. A chain tightener 174' is employed to exert the proper tension on the chain.

15 A second seaming tool comprises a roller 175 (Fig. 8) similar to the roller 158 but the peripheral groove 176 in this instance is more shallow than the groove 159, so that the seam is closed by this roller and a tight joint between the can body and cap is produced, as shown in Fig. 8. This roller is also provided with a central flange 177 which performs the same function as the flange 161 and also has a complementary groove 178, permitting reversal of the tool when desired. The tool 175 is mounted in a forked bar 179 which is likewise guided in a bracket 181, said bar being connected with a two-piece head 182 provided with a yielding member 183 similar to the member 169 and carrying a follower 184 which contacts with and is actuated by a cam 185 mounted on a shaft 186, also driven from the chain 174.

35 The parts are so timed and arranged that the seaming tools will be projected by their respective cams toward the turret between the successive movements of the turret so that each cap is preliminarily seamed to its body by the tool 158 and after the next movement of the turret the seaming operation is completed by the tool 175. The tools are retracted from operative position after the high portions of the cams have passed the followers by means of expansion springs 170. After the caps have been seamed onto the bodies the next movement of the turret carries the can into engagement with a knock-off guide bar 187 (Fig. 6) which causes 50 the can to drop out of its turret sockets into a delivery-chute 188, from which the can body with its cap seamed thereon is delivered at the rear end of the machine.

It is believed that my invention and its 55 mode of operation will be fully understood from the foregoing without further description and while I have shown and described a preferred embodiment of the invention it will be manifest that various changes in the size, shape and proportion of the parts disclosed may be made without departing from the spirit of the invention or sacrificing any of its material advantages.

I claim:

65 1. In a machine of the character de-

scribed, the combination of a horizontally disposed turret shaft, a can body and cap carrying turret disposed thereon, means for simultaneously feeding can bodies and caps to said turret, means for intermittently rotating said turret, a plurality of pairs of oppositely disposed chuck spindles, arranged in the path of movement of said can bodies and caps, means for moving the spindles at one end of said turret longitudinally with respect to said turret shaft, chuck heads fixedly secured to the longitudinally movable chuck spindles, the chuck spindles at the opposite ends of said turret being held from longitudinal movement with respect to said turret shaft and provided with yieldingly supported chuck heads, means for rotating each of said chuck spindles, and seaming means intermittently movable into co-operative relation with said can bodies and caps.

2. In a machine of the character described, the combination of a horizontally disposed turret shaft, a can body and cap carrying turret disposed thereon, means for simultaneously feeding can bodies and caps to said turret, means for intermittently rotating said turret, a plurality of pairs of oppositely disposed chuck spindles, arranged in the path of movement of said can bodies and caps, means for moving the spindles at one end of said turret longitudinally with respect to said turret shaft, chuck heads fixedly secured to the longitudinally movable chuck spindles, the chuck spindles at the opposite ends of said turret being held from longitudinal movement with respect to said turret shaft and provided with yieldingly supported chuck heads, means for rotating each of said chuck spindles, seaming means intermittently movable into co-operative relation with said can bodies and caps, and means for positively discharging the cans from said turret after the seaming operation.

3. In a machine of the character described, the combination of a horizontally disposed turret shaft, a can body and cap carrying turret disposed thereon, means for simultaneously feeding can bodies and caps to said turret, means for intermittently rotating said turret, a plurality of pairs of oppositely disposed chuck spindles arranged in the path of movement of said can bodies and caps, means for moving the spindles at one end of said turret longitudinally with respect to said turret shaft, chuck heads fixedly secured to the longitudinally movable chuck spindles, means for preventing longitudinal movement of the chuck spindles at the opposite end of said turret, chuck heads loosely mounted in said last-mentioned chuck spindles, yielding means normally forcing said loosely mounted chuck heads inwardly to can engaging position,

means for rotating each of said chuck spindles, and seaming means intermittently movable into coöperative relation with said can bodies and caps.

- 5 4. In a machine of the character described, the combination of a horizontally disposed turret shaft, a can body and cap-carrying turret disposed thereon, means for simultaneously feeding can bodies and caps to said turret, means for intermittently rotating said turret, a plurality of pairs of oppositely disposed chuck spindles arranged in the path of movement of said can bodies and caps, means for moving the spindles at 10 one end of said turret longitudinally with respect to said turret shaft, chuck heads fixedly secured to the longitudinally movable chuck spindles, means for preventing longitudinal movement of the chuck spindles at the opposite end of said turret, chuck heads 15 loosely mounted in said last-mentioned chuck spindles, yielding means normally forcing said loosely mounted chuck heads inwardly to can-engaging position, means for rotating each of said chuck spindles, adjustable members to receive the end 20 thrust of each of said chuck spindles, and seaming means intermittently movable into coöperative relation with said can bodies and caps.

- 30 5. In a machine of the character described, the combination of a horizontally disposed turret shaft, a can body and cap-carrying turret disposed thereon, means for simultaneously feeding can bodies and caps to said turret, means for intermittently rotating said turret, a plurality of pairs of oppositely disposed chuck spindles arranged in the path of movement of said can bodies 35 and caps remote from said feeding means, a reciprocating block adapted to support the spindles at one end of said turret, means for reciprocating said block, whereby said spindles are moved longitudinally of said 40 turret shaft, chuck heads fixedly secured to the longitudinally movable spindles, means for preventing longitudinal movement of the chuck spindles at the opposite end of said turret, chuck heads loosely mounted in 45 said last-mentioned chuck spindles, yielding means normally forcing said loosely mounted chuck heads inwardly to can-engaging position, means for continuously rotating each of said chuck spindles, and seaming 50 means intermittently movable into coöperative relation with said can bodies and caps.

- 55 6. In a machine of the character described, the combination of a horizontally disposed turret shaft, a can body and cap-carrying 60 turret disposed thereon, means for simultaneously feeding can bodies and caps to said turret, means for intermittently rotating said turret, a plurality of pairs of oppositely disposed chuck spindles arranged 65 in the path of movement of said can bodies

and caps remote from said feeding means, a reciprocating block adapted to support the spindles at one end of said turret, means for reciprocating said block, whereby said spindles are moved longitudinally of said 70 turret shaft, chuck heads fixedly secured to the longitudinally movable spindles, means for preventing longitudinal movement of the chuck spindles at the opposite end of said turret, chuck heads loosely mounted in 75 said last-mentioned chuck spindles, yielding means normally forcing said loosely mounted chuck heads inwardly to can-engaging position, means for continuously rotating each of said chuck spindles, adjustable members to receive the end 80 thrust of each of said chuck spindles, seaming means intermittently movable into coöperative relation with said can bodies and caps, and means for positively discharging the cans from said 85 turret after the seaming operation.

7. In a machine of the character described, the combination of a longitudinally disposed turret shaft, a can body and cap-carrying 90 turret disposed thereon, means for simultaneously feeding can bodies and caps to said turret, means for intermittently rotating said turret, a plurality of pairs of oppositely disposed chuck spindles disposed in the path of said can bodies and caps, remote 95 from said feeding means, means for moving the spindles at one end of said turret longitudinally with respect to said turret shaft, chuck heads fixedly secured to the longitudinally movable chuck spindles, the 100 chuck spindles at the opposite ends of said turret being held from longitudinal movement with respect to the turret shaft and provided with yieldingly supported chuck heads, means for rotating each of said chuck spindles, and resiliently mounted seaming 105 means intermittently movable into coöperative relation with the can bodies and caps.

8. In a can seaming machine, the combination of a turret mounted to rotate about a horizontal axis and provided with a series of radially disposed sockets, means for intermittently rotating said turret, a block slidably mounted adjacent one end of said 110 turret, a plurality of chuck spindles rotatably mounted in said block, chuck heads fixedly secured to said chuck spindles, means for reciprocating said block, whereby said chuck spindles are moved longitudinally with respect to said turret, a plurality of 115 chuck spindles mounted adjacent the opposite end of said turret and held from movement longitudinally of said turret, chuck heads yieldingly supported by each of said last-mentioned chuck spindles, and means for continuously rotating all of said chuck spindles.

9. In a can seaming machine, the combination of a turret mounted to rotate about a horizontal axis and provided with a series 120

of radially disposed sockets, means for rotating said turret by a step-by-step movement, a block slidably mounted adjacent one end of said turret, a plurality of chucks rotatably mounted in said block, means for reciprocating said block and the chucks carried thereby longitudinally of the turret, a plurality of chucks mounted adjacent the opposite end of the turret in alinement with said first-mentioned chucks, and means for continuously revolving all of said chucks.

10. In a can seaming machine, the combination of a turret provided with radially disposed sockets, a block mounted at one end of said turret and slideable longitudinally of the turret, a plurality of chuck spindles rotatably mounted in said block, a chuck head carried by each spindle, a plurality of spindles mounted at the opposite end of said turret in alinement with said first-mentioned spindles, means for rotating said turret by a step-by-step movement, and means for reciprocating said block between each successive actuation of said turret to project the chuck heads carried thereby into the ends of the adjacent turret sockets.

25. In a can seaming machine, the combina-

tion of a turret provided with can body sockets and can cap sockets, means for feeding can bodies and can caps to said sockets respectively, each cap socket being provided with a flange at its base to retain the cap therein, continuously rotating chuck spindles mounted at each end of said turret, chuck heads carried by said spindles, the inner face of the 35 chuck head adjacent the cap socket being disposed substantially in the radial plane of said cap socket flange, means for moving said cap chuck inwardly longitudinally of the turret to position the can cap against its corresponding can body, seaming means disposed in alinement with said positioned cap, and means for moving said seaming means into operative relation with the cap.

12. In a machine of the character described, a rotatable circular seaming roller having seaming grooves disposed about its periphery on opposite sides of a plane normal to the axis of said roller and substantially bisecting its periphery.
